FOREIGN PATENT DOCUMENTS

FR 3025407 A1 * 3/2016 ..... A45D 33/003

Primary Examiner — Jennifer Rivard(74) *Attorney, Agent, or Firm* — Browdy and Neimark, PLLC(57) **CLAIM**

The ornamental design for a combined cosmetic container and screen, as shown and described.

DESCRIPTION

FIG. 1 is a perspective view of a combined cosmetic container and screen as shown in the drawings;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged top plan view of the screen of FIG. 1. The screen is shown separately for convenience of illustration.

1 Claim, 8 Drawing Sheets(56)
